UNITED STATES PATENT OFFICE.

JOHN WOODHILL AND JAMES O'GORMAN, OF CLEVELAND, OHIO.

IRON FENCE.

SPECIFICATION forming part of Letters Patent No. 230,727, dated August 3, 1880.

Application filed June 21, 1880. (No model.)

To all whom it may concern:

Be it known that we, JOHN WOODHILL and JAMES O'GORMAN, of Cleveland, in the county of Cuyahoga and State of Ohio, have invented 5 certain new and useful Improvements in Fences; and we do hereby declare the following to be a full, clear, and exact description of the invention, such as will enable others skilled in the art to which it pertains to make and 10 use it, reference being had to the accompanying drawings, which form part of this specification.

Our invention relates to an improvement in iron fences; and it consists in attaching the 15 rails to the pickets by making recesses in the two opposite edges and fastening them to the rail by means of pronged balls which fit in the recesses and have their prongs extended down through openings in the rails, which 20 prongs are then bent or clinched against the upper side of the rail, so as to hold it rigidly in position.

Figure 1 is a side elevation of our invention. Fig. 2 is a vertical section of the same. 25 A represents a wrought-iron picket, preferably made square, as here shown, and which has a recess, B, formed in two of its opposite edges. These recesses, where the fence is to be built on horizontal ground, are made just 30 opposite each other; but where the fence is to be built upon uneven ground, one recess will be made higher than the other, just in proportion to the inclination of the ground.

The rail C has an opening made through it 35 for each picket, and which opening corresponds to the shape of the picket, and is placed at an angle to the length of the picket instead of a straight line therewith. In each of the 40 corners of this opening, which are in a line with the length of the rail, there is made a small recess, D, through which the prong G of the ball H is passed. This ball fits in the recess made in the edge of the rail, and has its prongs to extend down through the rail, as 45 shown. One of these balls is placed in each recess, and the prong of each ball is passed down through the rail, and after the rail has been moved tightly against the under side of the ball the prong is bent or clinched up against

the under side of the rail as tightly as possible, so as to throw the rail upward toward the ball. These balls being rigidly held in the recesses by means of the rail, just in proportion as the prong is bent or clinched against the under side of the rail so will the rail be rigidly locked to the picket. 50

As before stated, where the fence is placed upon level ground these recesses will be just opposite each other, and the rail will be locked in a horizontal position; but where the fence 60 is to be built upon inclined ground the rail will be inclined correspondingly, and will be locked rigidly in place equally as well whether in an inclined or horizontal position.

The spear-head I is made of cast-iron, and 65 has a socket made in its lower end to receive the upper end of the picket.

Extending downward from just under the center of the point of the head or spear is the dowel-pin O, which reaches to within about 70 one-eighth of an inch to the top of the socket, and against the lower end of this pin the upper end of the picket strikes when the head is placed in position.

Through the head, at the upper end of the 75 socket, there are made slight openings R, through which the two opposite corners of the pickets extend, and which corners can be riveted or hammered down over the top of the head, so as to lock the head rigidly upon the 80 picket.

Heretofore, in attaching a cast-iron head or spear-point, where the head has been cast upon the picket, there has always been a tendency of the two parts to separate, and the head has 85 been very easily broken off.

By means of this construction a wrought-iron picket and a cast-iron spear-head can be rigidly secured together at very little expense and trouble. 90

Having thus described our invention, we claim—

1. The combination of the picket having recesses in its opposite edges, with the rail and the pronged balls, substantially as shown. 95

2. In iron fences, the combination of a picket having the recesses in its two opposite edges, a rail for uniting the pickets together and

having an extension in the opening on each side of the two recessed edges of the picket, and the balls which fit in the recesses and having their prongs to project down through 5 the rail, and which prongs are clinched or bent outward against the under side of the rail, so as to lock it rigidly in place, substantially as shown.

In testimony that we claim the foregoing we have hereunto set our hands this 9th day of 10 June, 1880.

JOHN WOODHILL.
JAMES O'GORMAN.
